CLAIM

The ornamental design for a bug light trap, as shown and described.

DESCRIPTION

FIG. 1 is a front, left and top perspective view of a bug light trap showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area 9 in FIG. 1.

The broken lines in the figures illustrate portions of the bug light trap that form no part of the claimed design. The dot-dash broken lines represent boundaries of the enlarged portions and form no part of the claimed design.
